US0D1060500S

(12) United States Design Patent (10) Patent No.: US D1,060,500 S
(45) Date of Patent: * Feb. 4, 2025

(54) BINDER WITH ZIP

(71) Applicant: Shenzhen Zhongbai Chuangxiang Technology Co., Ltd., Guangdong (CN)

(72) Inventor: Yuxia Ma, Gansu (CN)

() Term: 15 Years

(21) Appl. No.: 29/967,075

(22) Filed: Oct. 8, 2024

(30) Foreign Application Priority Data

Jun. 5, 2024 (CN) 202430343903.4

(51) LOC (15) Cl. 19-04

(52) U.S. Cl.

USPC D19/26; D3/289

(58) Field of Classification Search

USPC D3/283, 284, 287, 288, 289, 303, 304, D3/314, 900, 902, 216, 217, 233, 245, D3/274, 276, 278, 286, 318; D19/26, 27, D19/76, 90, 113; D14/440; D6/631

Primary Examiner — L. A. Grabenstetter

Assistant Examiner — Danielle Nichole Bowly

(57) CLAIM

The ornamental design for a binder with zip, as shown and described.

DESCRIPTION

FIG. 1 is a front, right and top perspective view of a binder with zip, showing my new design.

FIG. 2 is a rear, right and top perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof.

FIG. 9 is a rear, right and top perspective view of the binder with zip, shown in an environment of use; and,

FIG. 10 is a rear, right and top perspective view of the binder with zip, shown in an environment of use.

The broken lines in the drawings depict portions of the binder with zip that form no part of the claimed design; the additional broken lines for the shoulder straps shown in FIGS. 9 and 10 are for purposes of illustrating environmental subject matter only and form no part thereof.

1 Claim, 10 Drawing Sheets
